US00D884673S

(12) **United States Design Patent** (10) Patent No.: **US D884,673 S**
(45) Date of Patent: **** May 19, 2020**

(54) **ELECTRONIC DEVICE**

- (71) Applicant: **Amazon Technologies, Inc.**, Seattle, WA (US)
- (72) Inventors: **Sun Joo Han**, San Francisco, CA (US); **Christopher Green**, San Francisco, CA (US); **Marc Rene Walliser**, San Francisco, CA (US); **Giles David Matthew McWilliam**, San Francisco, CA (US)
- (73) Assignee: **Amazon Technologies, Inc.**, Seattle, WA (US)

(**) Term: **15 Years**

(21) Appl. No.: **29/607,451**

(22) Filed: **Jun. 13, 2017**

(51) LOC (12) Cl. **14-02**

(52) U.S. Cl.

USPC **D14/216**; D14/356; D14/171; D10/2

(57) **CLAIM**

The ornamental design for an electronic device, as shown and described.

DESCRIPTION

FIG. 1 is a top perspective view of an electronic device; FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines depict portions of the electronic device that form no part of the claimed design.

1 Claim, 8 Drawing Sheets
